Mederhine Fairbanks

ATTORNEYS.

UNITED STATES PATENT OFFICE

CHARLES N. KOCH, OF KANE, PENNSYLVANIA

METHOD OF AND APPARATUS FOR FUEL CHARGING AND IGNITING

Application filed July 14, 1922. Serial No. 574,879.

(GRANTED UNDER THE ACT OF MARCH 3, 1883, AS AMENDED APRIL 30, 1928; 370 O. G. 757)

My method efficiently prepares, ignites and charges the fuel with its more or less volatile constituents, and may be practiced with many forms of apparatus.

5 The object of this device is to provide efficient means for confining the fuel under compression, igniting the fuel and discharging the ignited fuel to a desired source of utilization while in an incandescent state.

10 Another object is to have the explosion take place prior to the coincidence of the port in the cylindrical valve with the outlet port.

15 A further purpose of my invention is to provide a novel construction and arrangement of charge forming and igniting device wherein a plurality of explosion chambers are formed within a rotary valve mechanism, so that a continuous supply of incandescent gases can be provided.

20 With the above and other objects in view which will hereinafter appear, my invention comprehends a novel charge forming and igniting device.

It further comprehends other novel features of construction and advantage all as will hereinafter more clearly appear in the detailed description and the appended claim.

25 For the purpose of illustrating my invention, I have shown in the accompanying drawing a typical embodiment thereof which is at present preferred by me, since this embodiment will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

30 Figure 1 represents a sectional elevation of a charge forming and igniting device embodying my invention, the section being taken substantially on line 1—1 of Figure 4.

45 Figure 2 represents, in side elevation, a leak proof sealing ring employed.

Figure 3 represents a section on line 3—3 of Figure 1.

50 Figure 4 represents an end elevation of Figure 1.

Similar numerals of reference indicate corresponding parts.

Referring to the drawing.

1 designates a casing of a charge forming and igniting device, embodying my invention, said casing being provided with a water jacket 2 through which a cooling medium is circulated in any desired manner.

The casing 1 is provided with a removable end or head 3, which is secured in position by means of fastening devices 4.

5 designates a driving shaft, which is driven in any desired manner, preferably in timed relation with respect to the mechanism to which the incandescent or ignited gases are to be delivered. The shaft 5 is preferably hollow to provide for a circulation of atmospheric air therethrough to prevent the overheating of such shaft. This shaft 5 is journalled in the end head 3 and also in a bearing 6 and is provided with a thrust collar 7.

The shaft 5 has mounted thereon the valve shell 8, which revolves within the chamber 9 of the casing 1, and which forms rotary combustion chambers. The shell 8 is provided with closed ends and an intermediate partition 11 thereby dividing it into two explosion or combustion chambers 12 and 13, respectively.

The valve shell 8 is provided with a plurality of annular recesses 14, in each of which is seated a sealing ring 15 which is split for positioning in its said recess where it is fixed in position by means of dowel pins 16.

The sealing ring 15 is provided with a port 17 which registers with the respective port 18 or 19 formed in the valve shell 8. These openings lead each other by 180°.

Each chamber 12 and 13 are provided with an intake port 20 and a discharge port 21, see Figure 3.

Each chamber 12 and 13 are provided, respectively in cavities 12A, 13A, supplemental thereto in casing 1, with means for effecting the ignition or explosion of the charge such as, for example, spark plugs 22, which are controlled in timed relationship in any desired or conventional manner, such as by generator 22A, distributor 22B adapted to be driven by shaft 5 or otherwise, and spark 100

coil 22C, which may be electrically connected together and with spark plugs 22 as indicated in Fig. 1.

The operation of my novel charge forming 5 and igniting device will now be apparent to those skilled in this art and is as follows:—

The explosive mixture is introduced under pressure, in any desired manner, into the intake ports 20, and when the valve opening 10 18 or 19 is in register with its respective intake port, the explosive charge passes into the chamber 12 or 13.

In operation the shaft 5 and the walls of shell 8 become hot so that the fuel entering 15 inlet port 20, through its associated elongated port 17, 18, under pressure is impacted against hot shaft 5 and deflected into divided streams which are further impacted against the hot interior surface of rotating shell 8, 20 and thence further deflected to other surfaces of shell 8. Said impactings and deflections continue throughout the degrees of rotation of shell 8 in which said elongated port registers with inlet port 20 and 25 bring the fuel and air admitted through port 20 in contact with substantially the whole interior surface of said shell 8 associated with said elongated port, and materially reduces the temperature of said shaft and the walls 30 of shell 8 so that they do not exceed an efficient working temperature.

Said reduction in temperature causes a substantial increase in the temperature of the air and fuel successively impacted and deflected as aforesaid and tends to volatilize 35 the less volatile constituents of said fuel.

Said successive impactings and deflections of said fuel and air further creates turbulence which materially promotes combustion 40 and rapidity of flame propagation upon ignition.

After the valve has rotated into such position that its port is about to register with its respective discharge port 21, the ignition 45 takes place, and the ignited incandescent gases pass from the discharge port 21 to a desired point of utilization.

It will be apparent that while one chamber is having the exploded mixture discharged 50 therefrom, the other chamber is having explosive mixture introduced thereto.

It will be apparent that in accordance with my present invention, the entire volume of explosive mixture is ignited in a confined 55 space and is then discharged, so that the entire volume of incandescent gases is discharged at one time from an explosion chamber.

If used in conjunction with an internal 60 combustion turbine, the discharge of the ignited gases of the explosive mixture at high velocity through the passages 21 tends to produce a partial vacuum in chamber 12 or 13 wherein said ignition occurred, and which 65 tendency is increased by the movement of the

associated rotor member following its reception of the ignited gases and during the coincidence of the ports 21 and the ports in the rotary valve.

It will be apparent that in accordance with 70 my present invention, I employ a sleeve valve construction having a plurality of explosion chambers within which the explosion preferably alternately takes place on introducing the explosive mixture into such chambers 75 and the discharge of the ignited gases from said explosion chambers being controlled and timed by the valve.

It will be apparent that this invention is especially adapted for the use of light fuels 80 or of volatile fuels which can be ignited at moderate pressure in contradistinction to heavy fuels which are less volatile and which must be ignited under high pressure.

Special attention is directed to the ports 85 in the valves which, as shown in Figure 3, I prefer to illustrate as about 135° of port opening, it being apparent that this can be increased or diminished as may be considered desirable in practice. The dimensions of 90 the port opening would depend upon the speed at which the valve mechanism is to be operated. It will be seen that the explosion will take place just prior to the ports 19 and 17 communicating with their discharge port 95 21 and if a low degree of mixture is employed, the combustion will continue for a predetermined interval with the opening of these ports.

It will now be apparent that I have devised 100 a new and useful charge forming and igniting device for light fuels which embodies the features of advantage enumerated as desirable in the statement of the invention and the above description, and while I have, in 105 the present instance, shown and described a preferred embodiment thereof which will give in practice satisfactory and reliable results, it is to be understood that this embodiment is susceptible of modification in various 110 particulars without departing from the spirit or scope of the invention or sacrificing any of its advantages.

The invention herein described may be manufactured and used by and for the Government of the United States for governmental purposes without the payment to me of any royalty thereon or therefor.

Having thus described my invention, what I claim as new and desire to secure by Letter Patent, is:

A combined charge forming and ignition device for producing a continuous flow of incandescent gas under high pressure comprising a casing having a plurality of intake 125 and exhaust ports, a shaft journaled within the ends of the said casing, said shaft being hollow to permit circulation of a cooling medium therethrough, a rotary shell within the casing having a plurality of combustion 130

chambers, with said shaft extending across each of said chambers in alignment with the flow of fuel from said intake ports each of said chambers having combined inlet and outlet openings, said openings being so related to each other and so related to the exhaust and inlet ports of the casing that the rotation of the shell will produce progressively a substantially continuous inlet and exhaust for said chambers and means whereby an ignition spark may be provided for each of the chambers at about the time its opening registers with an exhaust port of the casing.
